United States Patent

Des. 235,454
Patented June 17, 1975

235,454

BATTERY CARRIER

Albert A Lindow, Jr., 1761 Brett Ave.,
Pittsburgh, Pa. 15205

Filed Sept. 10, 1973, Ser. No. 395,768

Term of patent 14 years

Int. Cl. D13—02

U.S. CL. D26—6

FIG. 1.

FIG. 2.

FIG. 3.

FIG. 4.

FIG. 5.

FIG. 6.

FIG. 1 is an exploded perspective view of a battery carrier showing my design;

FIG. 2 is a view showing the components of my battery carrier in assembled relationship;

FIG. 3 is a top view thereof;

FIG. 4 is a front view thereof;

FIG. 5 is an end view thereof;

FIG. 6 is a bottom view thereof.

I claim:

An ornamental design for a battery carrier, substantially as shown.
